AUTOMATIC ELECTRIC HOT-WATER
HEATING SYSTEM

Daniel J. Limerick, Hammond, Ind.

Application December 22, 1949, Serial No. 134,387

2 Claims. (Cl. 219—38)

1

My invention relates to an automatic hot water heating system.

A primary object of my invention is to provide an automatic electric hot water heating system for use in homes and small offices, the system being highly simplified and extremely compact.

A further object is to provide a novel electric hot water heater including separate, independent, electric heating elements which may be removed individually for repairs and the like without shutting down the entire heating system or draining the boiler.

A further object is to provide a compact and relatively small, automatic electric heating system which will produce a steady and even heat at all times.

A still further object of the invention is to provide a heating system of the above-mentioned character which will be economical to install and operate.

Other objects and advantages of the invention will be apparent during the course of the following description.

In the accompanying drawings forming a part of this application, and in which like numerals are employed to designate like parts throughout the same:

Figure 1 is a side elevation of an automatic electric hot water heating system embodying my invention, partly diagrammatic;

Figure 2 is a central, vertical section taken on line 2—2 of Figure 1;

Figure 3 is a horizontal, transverse section taken on line 3—3 of Figure 1;

Figure 4 is an enlarged fragmentary, horizontal section taken on line 4—4 of Figure 3; and

Figure 5 is a diagrammatic view of an electrical circuit embodied in my heating system.

In the drawings, where, for the purpose of illustration, is shown a preferred embodiment of my invention, the numeral 10 designates the floor of a house or the like supported by the usual horizontal floor joists 11. Conventional hot water radiators 12 and 13 are mounted upon the floor 10 in spaced-apart relation, and may be disposed in different rooms of the house.

A relatively small, compact, electric hot water heater or boiler 14 may be arranged below the floor 10 and suspended from the floor joists 11 by means of depending vertical bars or plates 15 having their top ends rigidly secured to adjacent joists 11 and their bottom ends detachably connected, as at 16, with upstanding lugs 17 rigidly secured to the top of the heater or boiler.

2

14. The boiler 14 is also equipped at its bottom with legs 18 which support the boiler when it is desired to mount the boiler upon a basement floor or the like.

5 The heater or boiler proper comprises a generally cylindrical shell or casing 19 formed of steel, cast iron or the like. This casing 19 includes a conically tapered top 20 and a flat, horizontal bottom 21, the top and bottom being 10 integrally connected with the side wall of the casing to form a water-tight chamber or compartment adapted to be filled with water. The top 20 of the boiler has a short vertical hot water outlet pipe 22 having a T-fitting 23 secured to its 15 top end, and connected with horizontally disposed pipes 24 and 25, leading at their opposite ends into vertically upwardly extending hot water inlet pipes 26 and 27 leading into the bottoms of the radiators 12 and 13 at one pair of 20 ends of the radiators, as shown in Figure 1. Vertical return pipes 28 and 29 lead from the tops of the radiators 12 and 13, and from their opposite ends. The return pipe 28 extends below the floor 10 for a slight distance, and leads into a 25 horizontal branch pipe 30, having its end connected with a T-fitting 31, in turn connected in the vertically extending return pipe 29 of the radiator 13. The pipe 29 extends adjacent to the bottom of the boiler 14 for connection with an elbow 32 leading into a horizontal pipe 33 connected at its opposite end with an elbow 34, in turn connected with a short, vertical return pipe 35 leading into the bottom 21 of the boiler at the center of the boiler and in substantial alignment with the outlet pipe 22.

30 The forward side of the boiler is provided with a large, rectangular opening 36 bounded at its opposite sides with vertically extending, forwardly projecting flanges or door jambs 37 and 38. 35 The flanges 37 and 38 are flat and integrally connected, by welding or the like, with the cylindrical shell or casing 19. The entire outer surface of the cylindrical casing 19, the outer surfaces of the flanges 37 and 38, and the outer faces 40 of the top and bottom 21 and 22, respectively, are all preferably lagged or coated with asbestos 45 39, or any other suitable heat-insulating compound. An outer jacket 40 of sheet metal or the like may be provided upon the outer surface of the asbestos coating, and this jacket or covering 40 preferably includes a top and bottom section 41 and 42, respectively, and side flanges 43 and 44 spaced laterally outwardly of the flanges 37 and 38.

50 55 A large, rectangular, slightly transversely con-

vex door 45 is provided for covering the forward opening 36, and this door is mounted upon hinges 46 for horizontal swinging movement, the hinges being rigidly secured to the adjacent flanges 38 and 44. The outer face of the door 45 is likewise preferably coated or lagged with asbestos 47, in turn preferably covered with an outer sheet metal jacket 48. If desired, the door 45 need not be covered with asbestos, as shown, but may be provided with separate asbestos inserts upon its inner face to cover the forward openings of the heating cells, to be described.

Three separate, flat and relatively low internal heating cells 49, 50 and 51 are provided and arranged in vertically spaced, superposed relation, as shown in Figure 2. The cells 49, 50 and 51 are horizontal, as shown, and each shell comprises a flat top and bottom 52 and 53, respectively. Each shell further comprises a vertical, narrow side wall 55 cylindrically curved at its inner end, as shown at 56, and spaced radially and concentrically from the side wall of the casing 19, Figure 3. The tops, bottoms and side walls of the cells 49, 50 and 51 are integrally connected by welding or the like to form dry watertight compartments within the cells. The cells 49, 50 and 51 project laterally inwardly from the opening 36 toward and near the rear side of the casing 19, and the inner ends of the cells are supported by rigid, horizontal I-braces 57 having their opposite ends welded or otherwise rigidly secured to the side wall of the casing 19. The forward ends of the cells are open until covered by the door 45, and such forward ends project through the forward opening 36 and terminate flush with the outer vertical edges of the flanges or door jambs 37 and 38, such flanges being integrally connected by welding or the like with the side walls 55 of the cells. The construction is such that the casing or tank 19 may be entirely filled with water, while the compartments formed by the cells 49, 50 and 51 remain entirely dry, although the cells are completely surrounded by and submerged in the water. Likewise, due to the integral welded construction, no water can leak from the tank or casing 19 through the forward opening 36.

Fixedly mounted within each of the cells 49, 50 and 51 is a horizontally disposed, circular, electric resistance type heating element 59, preferably comprising a plurality of coils and engaging upon low, tapered or cone-shaped blocks 60 of insulating material, such blocks serving to support and center the heating elements 59 within the cells. The heating elements or coils 59 have radial ends 61 and 62 bent laterally outwardly adjacent to the forward opening 36 for passage through openings 63 formed in the adjacent side flange 37 and jacket side 43. As best shown in Figure 4, the lateral extensions 64 and 65 of the heating elements 59 are embedded in electrical insulating material 66 covered with suitable sheathing or tubing 67 for engagement through the openings 63. The inner face of the door 45 is recessed, as shown in Figure 3, to accommodate the extensions 64 and 65. The heating elements or coils 59 are of the type generally employed in conventional electric kitchen ranges and the like. The heating elements 59 are adapted to operate within their dry compartments formed by the cells 49, 50 and 51 to heat the water in the casing 19 surrounding the cells.

As shown in Figures 1 and 5, a conventional wall-mounted, room-temperature control device or thermostat 68 is arranged within the room

having the radiator 12, and the thermostat 68 is connected with wires 69 and 70. A main control switch 73, having terminals 71 and 72, is connected in lines or wires 74 and 75 leading from the source of current. The numerals 76 and 77 designate aquastat switches. These aquastat switches 76 and 77 are connected in the hot water inlet pipe 27, Figure 1, and are actuated by changes in temperature of the water flowing through the pipe 27. The aquastat switch 76 is connected with wires 78 and 79, electrically connected, as at 80 and 81, with a pair of terminals of a control panel or terminal strip 82. The second aquastat switch 77 is connected with wires 83 and 84, electrically connected, as at 85 and 86, with the terminal strip 82. The thermostat wires 69 and 70 are electrically connected in the wires 74 and 75, between the main switch 73 and control panel 82, as at 69' and 70'. In Figure 5, the three heating elements 59 are shown in their same relative positions, one above the other, as shown and described in connection with Figure 2. The intermediate and lowermost heating elements 59 are electrically connected in series, Figure 5, and the uppermost heating element 59 is connected in parallel with the lowermost and intermediate elements 59. The uppermost element 59 has one end wire 87 electrically connected, as at 88, with the terminal strip 82, and the other end wire 89 of the uppermost heating element 59 is electrically connected, as at 90, with the terminal strip 82. One end wire 91 of the intermediate element 59 is electrically connected at 92 with the terminal strip 82, and the opposite end wire 93 of the lowermost elements 59 is connected, as at 94, with the wire 89 leading to the terminal strip at 90. With this arrangement, the uppermost heating element may be operated alone with the intermediate and lowermost heating elements cut off. The aquastat switch 77 is preferably set for water temperatures ranging from 180° to 195°, and will cut in at 180° and shut off at 195°. The aquastat switch 76 is adjusted to cut off at water temperatures of 210°. The aquastat switch 77 controls the operation of both the intermediate and lowermost heating elements 59 which are connected in series, as previously stated, while the aquastat switch 76 controls the operation of the uppermost heating element 59. The aquastat switch 76 is adapted to turn on or energize the uppermost heating element 59 when the water within the pipe 27 reaches approximately 195°.

In operation, with the heating system hooked up as shown and described, the main switch 73 is in the line is closed and the thermostat 68 is set for the desired room temperature. Assuming that the water in the pipe 27 is cold, both aquastats 76 and 77 are closed, so that all three heating coils 59 will produce heat. The water within the boiler casing 19 is now heated and will begin to circulate upwardly through the pipe 22, horizontal pipes 24 and 25, vertical inlet pipes 26 and 27, and into the bottoms of the radiators 12 and 13 to heat the same. The hot water gives up its heat in passing through the radiators, and returns to the bottom of the boiler through the return pipes 28 and 29, horizontal pipe 33, and short, vertical return pipe 35, leading into the bottom of the boiler. When the water in the pipe 27 reaches approximately 195°, the aquastat switch 77 will cut off or de-energize the intermediate and lowermost heating elements 59 and the other aquastat switch 76 will maintain the uppermost heating element 59 energized until the maximum desirable water temperature is reached.

If the temperature of the water in the system rises to approximately 210°, the aquastat 76 will be actuated for cutting off the uppermost heating element 59.

It is thus seen that completely automatic means are provided for efficiently and rapidly heating the water within the boiler 14 to approximately the desired temperature, and further automatic means operate a separate heating element for maintaining the heated water at substantially its maximum temperature. Obviously, I do not wish to limit the invention to the precise temperature ranges mentioned previously for actuating the aquastat switches 76 and 77, and these temperature ranges may be accordingly varied.

The construction of the boiler 14 is such that when it becomes necessary to remove or repair one of the heating elements 59, it is unnecessary to drain the water from the boiler or to completely shut off the heating system. The system is very simple, compact, and occupies a minimum of space. It is particularly well adapted for use in small homes and offices.

It is to be understood that the form of my invention herewith shown and described is to be taken as a preferred example of the same, and that various changes in shape, size and arrangement of parts may be resorted to without departing from the spirit of the invention or the scope of the subjoined claims.

Having thus described my invention, I claim:

1. A heating system comprising a radiator mounted upon the floor of a room, a boiler arranged below said floor and dependingly supported from the latter, a pipe having one end connected to the bottom of said boiler and having the other end connected to said radiator adjacent its top for conveying water from said radiator to said boiler, a second pipe having one end in communication with the top of said boiler and having the other end connected to said radiator adjacent the bottom thereof for conveying water from said boiler to said radiator, a plurality of horizontally disposed cells arranged in superimposed spaced relation mounted within said boiler, an electrical heating unit positioned in each of said cells, a source of electrical energy, means connecting the heating unit in each of said cells to said source, a first temperature responsive means operatively connected to said

second pipe and the heating unit of one of said cells for heating the water in the boiler to a predetermined temperature, and a second temperature responsive means operatively connected to said second pipe and to the heating unit in another of said cells for maintaining the water in said system at a substantially maximum constant temperature.

2. A heating system, comprising a radiator mounted upon the floor of a room, a boiler arranged below said floor and dependingly supported from the latter, a pipe having one end connected to the bottom of said boiler and having the other end connected to said radiator adjacent its top for conveying water from said radiator to said boiler, a second pipe having one end in communication with the top of said boiler and having the other end connected to said radiator adjacent the bottom thereof for conveying water from said boiler to said radiator, at least three horizontally disposed cells arranged in superimposed spaced relation mounted within said boiler, an electrical heating unit positioned in each of said cells, a source of electrical energy, means connecting the heating unit in each of said cells to said source, a first temperature responsive means operatively connected to said second pipe and the heating units of two of said cells for heating the water in the boiler to a predetermined temperature, and a second temperature responsive means operatively connected to said second pipe and to the heating unit in the other of said cells for maintaining the water in said system at a substantially maximum constant temperature.

DANIEL J. LIMERICK.
